United States Patent Office.

CHRISTOPHER MEYER, OF NEW YORK, N. Y.

Design No. 4,862, dated May 2, 1871.

DESIGN FOR RUBBER SHOES.

The Schedule referred to in these Letters Patent and making part of the same.

To all whom it may concern:

Be it known that I, CHRISTOPHER MEYER, of New York city, in the county and State of New York, have invented a new and improved Design for India-Rubber Shoes; and I do hereby declare that the following is a full, clear, and exact description thereof, which will enable others skilled in the art to make and use the same, reference being had to the accompanying drawing forming part of this specification.

My improved design consists in the pairs of raised transverse ribs *a* across the top and instep united at the ends *b*, in connection with the raised rib *d*

crossing the toe, and extending along the sides to the sides of the heel, and up to the rib *e*; also the said rib *e* extending around the top of the shoe, all as clearly represented in the accompanying drawing, to which reference is made.

I claim as my invention—

The design for India-rubber shoes, as set forth and shown.

C. MEYER.
